CLAIM

The ornamental design for a docking station for a robotic platform, as shown and described.

DESCRIPTION

FIG. 1 is a front-perspective view of a docking station for a robotic platform, according to an embodiment;

FIG. 2 is a back-perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken lines in the drawings depict portions of the docking station for a robotic platform and from no part of the claimed design.

1 Claim, 8 Drawing Sheets

Matter enclosed in heavy brackets [ ] appears in the original patent but forms no part of this reissue; matter printed in italics indicates the additions made by reissue.
